197,671

STORAGE BAG FOR UNDERGARMENTS
OR THE LIKE

Dorothy W. Styer, 1011 La Cadena Drive,
Riverside, Calif.

Filed May 16, 1963, Ser. No. 74,912

Term of patent 14 years

(Cl. D58—2)

Fig. 1

Fig. 2

FIGURE 1 is a front isometric view of a storage bag for undergarments or the like embodying my new design; and

FIGURE 2 is a rear isometric view of same.

The dominant features of my design reside in the portions shown in full lines.

I claim:

The ornamental design for a storage bag for undergarments or the like, substantially as shown and described.

References Cited in the file of this patent

UNITED STATES PATENTS

D. 115,502	Kohl	July 4, 1939
2,177,906	Miller	Oct. 31, 1939
3,039,599	Mintz	June 19, 1962

OTHER REFERENCES

Notion and Novelty Review, March 1950, p. 21, third item from top, right side of page.